UNITED STATES PATENT OFFICE.

HORACE P. BROWN, OF SAN FRANCISCO, CALIFORNIA.

MANIFOLDING-TABLET.

SPECIFICATION forming part of Letters Patent No. 760,608, dated May 24, 1904.

Application filed March 29, 1902. Serial No. 100,638. (No model.)

To all whom it may concern:

Be it known that I, HORACE P. BROWN, a citizen of the United States, residing at San Francisco, in the county of San Francisco and State 5 of California, have invented certain new and useful Improvements in Manifolding-Tablets, of which the following is a specification.

This invention relates to a case for holding a manifold-strip and enabling portions to be 10 easily withdrawn. The case is especially intended for use with a manifold-strip consisting of a long sheet of paper folded longitudinally to give a plurality of superposed portions and folded transversely into a zigzag. 15 A strip of carbon-paper may be interposed between the layers; but the transfer material is preferably a permanent carbon coating on the back of the superposed portions.

Referring to the accompanying drawings, 20 Figure 1 is a perspective view of the manifold-tablet with a portion of the strip withdrawn. Fig. 2 is a perspective view of the empty case from the rear, showing its covers partly open. Fig. 3 is a central longitudinal 25 section of the case, the strip therein being indicated by broken lines; and Fig. 4 is a plan view of a portion of the manifold-strip before it is folded longitudinally and transversely.

The manifold-case consists of a rectangular 30 box 1, of suitable material, such as aluminium or other sheet metal, covered with thin leather or cloth. The rear open side of the box is closed by two covers 2 3. The cover 2 is carried by pivots 4, secured to one end of the 35 box near its rear edge. This cover extends only to the middle of the box and has at its free end a small roller 5, pivoted at its ends in pieces 6, which are secured to or integral with the sides of the cover. The cover 3 is 40 secured to the other end of the box by hinges 7 and has flanges 8, which inclose the sides of the box. The sides of the box have extensions 9 at the upper end, between which is pivoted a roller 10. The cover 3 has curved 45 fingers 11, which extend partly around the roller 10. The box is provided with means for retaining a card 12 on its upper face—for example, clips 13, extending from the sides

of the case over the face. The cover 3 may, if desired, be provided with means for locking it when closed.

Fig. 4 shows a blank for the manifold-strip before it is folded for insertion into the case. This blank comprises a long strip of suitable material, having longitudinal lines of perforation 14 and 15 and transverse lines of perforation 16. As shown, the portion 17 of the strip has on its rear face a permanent coating 18 of carbon or other transfer material. The intermediate portion 19 has on its upper face 60 a similar coating 20. For use the strip is first folded upon the line 14, so that the carbon coating 18 of the upper portion 17 overlies the blank face of the intermediate or duplicate portion 19. The strip is then folded upon 65 line 15, so that the coating 20 on the back of the duplicate overlies the triplicate 21. The manifold-strip is then folded into a zigzag on the transverse lines 16, whereupon it is ready 70 for insertion into the case.

For use the outer end of the manifold-strip lying within its case 1 is pulled out around the roller 10, being guided by the fingers 11. It is then drawn down upon the card 12, whereupon the first transverse line of perforations 16 lies just above the roller 10. The memoranda now written on the upper portion 17 of the strip are by reason of the carbon coatings 18 and 20 reproduced upon the face of the duplicate 19 and the triplicate 21. The 80 original duplicate and triplicate when filled out are detached from the strip along lines 16 and separated from each other along the lines 14 15.

The half-cover 2, with its end roller 5, 85 causes the strip to be smoothly withdrawn from the case without buckling, such as would occur if the strip were pulled out from a slot at the end of the case.

While the case shown and described is especially intended for use with a manifold-strip, it is obviously a desirable holder for any strip of material which is folded into a zigzag, such as one of wrapping or toilet paper.

The term "guide for the strip" as used in 95 the claims is intended to cover the roller 10

or any equivalent device which will facilitate the passage of the strip from the case to the writing-support as it is being withdrawn.

I claim—

- 5 1. A case for retaining and feeding out a strip folded transversely into a zigzag, said case having a device at about its middle portion to guide the strip while being withdrawn, a passage for the withdrawal of the strip, a writing-support, and a guide for the strip between said passage and support, as set forth.
- 10 2. A case for retaining and feeding out a strip folded transversely into a zigzag, said case having a device at about its middle portion to guide the strip while being withdrawn, a passage for the withdrawal of the strip, a writing-support, and a guide for the strip between said passage and support, as set forth.
- 15 3. A case for retaining and feeding out a strip folded transversely into a zigzag, said case having a roller at about its middle portion to guide the strip while being withdrawn, a passage for the withdrawal of the strip, a writing-support, and a guide for the strip between said passage and support, as set forth.
- 20 4. A case for retaining and feeding out a strip folded transversely into a zigzag, said case having a roller at about its middle portion to guide the strip while being withdrawn, a passage for the withdrawal of the strip, a writing-support, and a guide for the strip between said passage and support, as set forth.
- 25 5. A case for retaining and feeding out a strip folded transversely into a zigzag, said case having a roller at its middle portion to guide the strip while being withdrawn, a passage for the withdrawal of the strip, a writing-support, and a roller to carry the strip between said passage and writing-support, as set forth.
- 30 6. A case for retaining and feeding out a strip folded transversely into a zigzag, having a passage for the strip extending out through the case near one end, a writing-support, and a roller to carry the strip between said passage and writing-support, as set forth.
- 35 7. A case for retaining and feeding out a strip folded transversely into a zigzag, having a passage for the strip extending out through the case near one end, a writing-support, a roller to carry the strip between said passage and writing-support, and a plurality of separate, flexible curved guides for the strip extending partly around said roller, as set forth.
- 40 8. A case for retaining and feeding out a strip folded transversely into a zigzag, said case having a movable half-cover carrying at its free end a guide to facilitate withdrawal of the strip, as set forth.
- 45 9. A case for retaining and feeding out a strip folded transversely into a zigzag, said case having a movable half-cover carrying at its free end a roller to facilitate withdrawal of the strip, as set forth.

10. A case for retaining and feeding out a strip folded transversely into a zigzag, said case having a movable half-cover carrying at its free end a guide to facilitate withdrawal of the strip, and a full cover inclosing the half-cover but leaving a passage for the strip, as set forth.

11. A case for retaining and feeding out a strip folded transversely into a zigzag, said case having a movable half-cover carrying at its free end a roller to facilitate withdrawal of the strip, and a full cover inclosing the half-cover but leaving a passage for the strip, as set forth.

12. A case for retaining and feeding out a strip folded transversely into a zigzag, said case having a roller to facilitate withdrawal of the strip, a passage for the withdrawal of the strip, a writing-support, and a second roller between said passage and support, as set forth.

13. A case for retaining and feeding out a strip folded transversely into a zigzag, said case having a movable half-cover carrying at its free end a roller to facilitate withdrawal of the strip, a passage for the withdrawal of the strip, a writing-support, and a second roller between said passage and support, as set forth.

14. A case for retaining and feeding out a strip folded transversely into a zigzag, said case having a movable half-cover carrying at its free end a roller to facilitate withdrawal of the strip, a full cover inclosing the half-cover but leaving a passage for the strip, a writing-support, and a second roller between said passage and support, as set forth.

15. The combination with a manifolding-strip, comprising a sheet folded longitudinally to give superposed portions and folded transversely into a zigzag, of a case containing said strip and having a guide at about its middle portion to facilitate withdrawal of the strip, as set forth.

16. The combination with a manifolding-strip, comprising a sheet folded longitudinally to give superposed portions and folded transversely into a zigzag, of a case containing said strip and having a roller at about its middle portion to facilitate withdrawal of the strip, as set forth.

17. The combination with a manifolding-strip, comprising a sheet folded longitudinally to give superposed portions and folded transversely into a zigzag, of a case containing said strip, said case having a half-cover with its end in position to facilitate withdrawal of the strip, and a full cover inclosing the half-cover but leaving a passage for the strip, as set forth.

18. The combination with a manifolding-strip, comprising a sheet folded longitudinally to give superposed portions and folded transversely into a zigzag, of a case contain-

ing said strip, said case having a half-cover with its end in position to facilitate withdrawal of the strip, a full cover inclosing the half-cover but leaving a passage for the strip, and 5 a roller at the end of the case, as set forth.

19. A case for retaining and feeding out a strip folded transversely into a zigzag, said case having a half-cover with its end in position to cause the strip to be withdrawn from 10 about the middle of the folded portions, a full cover inclosing the half-cover and strip, a roller at the end of the case, and fingers extending from the full cover partly around the roller, as set forth.

15 20. A case for retaining and feeding out a

strip folded transversely into a zigzag, said case having a half-cover provided with a roller at its end in position to cause the strip to be withdrawn from about the middle of the folded portions, a full cover inclosing the half- 20 cover and strip, a roller at the end of the case, and fingers extending from the full cover partly around the latter roller, as set forth.

In testimony whereof I affix my signature in presence of two witnesses.
